UNITED STATES PATENT OFFICE.

JOSEPH LAWTON DIXON, OF DETROIT, MICHIGAN.

ELECTRIC FURNACE.

1,197,458.

Specification of Letters Patent.

Patented Sept. 5, 1916.

Original application filed February 23, 1915, Serial No. 9,782. Divided and this application filed April 10, 1916. Serial No. 90,081.

To all whom it may concern:

Be it known that I, JOSEPH L. DIXON, a subject of the King of Great Britain, residing in the city of Detroit and State of Michigan, have invented certain new and useful Improvements in Electric Furnaces; and I do hereby declare the following to be a full, clear, and exact description of the invention, such as will enable others skilled in the art 10 to which it appertains to make and use the same.

My present invention relates to that class of electric smelting furnaces wherein the current may be made to pass either from one 15 electrode to another over the bath or from one or more of these either wholly or in part through the bath and furnace lining.

The object of my invention is to supply an improved construction for electric smelting furnaces of this kind, whereby two-phase currents, fed from specially arranged 20 transformers, are made controllable as to their phase relations by suitable switches, so as to cause different proportions of the total 25 current to flow through the bath and lining.

It is a further object of the invention to accomplish these ends without unbalancing the load on the feeding means.

Certain preferred embodiments of the invention are illustrated diagrammatically in 30 the accompanying drawings wherein—

Figure 1 shows a furnace having two pairs of upper electrodes supplied with two-phase alternating current, Figs. 2 to 8 inclusive 35 are vector diagrams illustrative of altered phase conditions produced by various changes in the electric connections shown in Fig. 1, Fig. 9 illustrates a modified form wherein six upper electrodes are employed, 40 and Figs. 10 and 11 are vector diagrams indicating different phase relations producible in the form of furnace shown in Fig. 9.

In Fig. 1 the usual hearth, crucible or container is shown at 10, the molten bath within 45 it is shown at 11, while the four upper electrodes 12, 13, 14 and 15 project downward toward the bath through the insulating cover 16. The current which passes downward through the bath, when so desired, returns 50 through the lower electrode 17.

The working current is derived from the three-phase alternating current means 18, 19 and 20, being directly supplied from the low voltage secondaries of the four trans-

formers 21, 22, 23 and 24, in the form of 55 two-phase current. Considered by themselves, the transformers 21 and 22 may be described as two "Scott-connected" transformers, delivering secondary currents according to a system known as the "two phase-three 60 wire system." For this purpose the primaries of these transformers are connected to each other and to the feeding mains in the well known manner shown, while the lower voltage secondaries have their outer terminals connected respectively to the upper electrodes 12 and 13, and their inner terminals connected in common to the lower electrode 17. The second pair of transformers 23 and 24 are similarly connected to the mains and 70 the furnace electrodes 14, 15 and 17 respectively; save that the wires leading to the mains are connected thereto by means of separate multiple switches 25 and 26. By means of these switches the connections of 75 the transformers 23 and 24 may be reversed with respect to two of the three feeding or main wires. When the switch 26 is closed (the switch 25, of course, being open) the 80 transformers 23 and 24 are connected to the mains 18, 19, 20, in a reverse manner with relation to the connections of the transformers 21 and 22. When connected thus, the 85 phase relations existing in the four upper electrodes are as indicated in Fig. 2; that is to say the phases in the upper electrodes 12 and 14 are 180 degrees apart, as are also those in electrodes 13 and 15. Therefore, if the four currents are of equal magnitude 90 there is no current passing through the bath to the lower electrode 17.

The precise connections of the transformers 23 and 24 as shown in Fig. 1 are merely an example of the possibilities of the system. For instance if (with the switch 26 closed) 95 only one instead of both of the primaries of 23 and 24 is reversed with respect to the corresponding transformer 21 or 22, the secondary currents will have the phase relation shown in Fig. 3, in which case the current 100 through the bath will be equal to 2; unity being the current in each of the upper electrodes (it being assumed that these are all kept equal). By another obvious change in connections, the relation of phases shown in 105 Fig. 4 is obtained. In this case the current through the bath and lower electrode will be 2.82. If, now, in Fig. 1, the switch 25 is

closed (26 being open) the phase relation shown in Fig. 5 will result. In this case the current through the bath will be .73. Starting from this position and reversing one or more of the phases by appropriate changes in connections we may obtain the phase relations shown respectively in Figs. 6, 7, and 8. In these cases the current through the bath amounts to 1.4, to 2.73 and 10 to 2.45 respectively. It is thus apparent that, by using two multiple switches as shown, any two of the seven phase relations shown in Figs. 2 to 8 may be obtained. By increasing the number of switches with 15 varied connections a greater number of phase relations becomes available, with a correspondingly greater number of current values through the bath and lower electrode.

In Fig. 9 is shown another embodiment 20 of the invention suited to a larger furnace, having an increased capacity and furnished with six instead of four upper electrodes. These electrodes are numbered 27, 28, 29, 30, 31 and 32, and are directly supplied with 25 two-phase alternating current from six transformers, 33, 34, 35, 36 37 and 38 connected in pairs as shown. Two of these pairs are permanently "Scott connected" to the mains 18, 19 and 20, on their primary side; 30 while the primaries of the third pair are similarly connected to said mains through two multiple switches 39 and 40, each having preferably four movable switch members, and the innermost movable members 35 of the two sets being permanently connected to each other and to the middle of the primary 38. As before, the low voltage secondaries of all the transformers are connected by the two-phase three wire system to 40 their respective pairs of upper electrodes. When the switch 40 is closed the phase relations are such as are shown in the vector diagram, Fig. 10. In this case, if the upper electrodes are supplying currents of 45 equal magnitudes among themselves, there will be no current through the bath and lower electrode.

Obviously, a great number of variations 50 in phase relations can be here produced by reversals of the connections of the individual transformers, and a correspondingly great variation is possible in the amount of current which is made to pass through the bath. These changes are all consistent with 55 keeping the current magnitudes equal among the upper electrodes. This variety of phase relations can be still further increased by making changes in connections other than simple reversals. If now the multiple 60 switch be opened and switch 39 closed, the phase relations produced are those shown in Fig. 11; and if the currents are kept equal to unity in each of the six upper electrodes, the value of the current through the bath and lower electrode will be .73.

While, for purposes of simplicity, I have shown only furnaces with four and with six upper electrodes, it is to be understood that the invention covers the use of any number of pairs greater than one.

This application is a division of my earlier application for improvement in electric furnaces, filed February 23, 1915, Serial No. 9782.

What I claim is:—

1. An electric furnace having a lower electrode and a plurality of pairs of upper electrodes, feeding mains adapted to supply alternating current, a pair of transformers for each pair of upper electrodes, each pair having its outer secondary terminals connected with appropriate upper electrodes and its inner terminals connected in common with the lower electrode, and the primary of each pair of transformers being connected with 85 said mains; and multiple switches for changing the current phases in some of the coils of one of said pairs of transformers.

2. An electric furnace having a lower electrode and a plurality of pairs of upper electrodes, feeding mains adapted to supply three-phase alternating current, a pair of "Scott-connected" transformers for each pair of upper electrodes, each pair having its outer secondary terminals connected with appropriate upper electrodes and its inner secondary terminals connected with the lower electrode, suitable conductors for connecting the primaries of said transformers with said feeding mains and switches in circuit with said last named conductors adapted to alter the current phases in some of the coils of one of said pairs of transformers.

3. An electric furnace having a lower electrode and a plurality of pairs of upper electrodes, feeding mains adapted to supply three-phase alternating current, a pair of "Scott-connected" transformers for each pair of electrodes, each pair being connected on its secondary side by the two-phase three wire system to said furnace, and on its primary side with said feeding mains, and two three-part multiple switches with suitable connecting conductors, adapted to alter the current phases in some of the coils of one of 115 said pairs of transformers.

4. In an electric furnace equipment of the class described, alternating current feeding mains, a number of pairs of transformers having permanent connections with said mains, and an additional pair of similar transformers intended to have its feeding connections altered; in combination with switches and connecting conductors suitably arranged to accomplish alteration of current phases in some of the coils of said additional pair.

5. In an electric furnace equipment of the class described, feeding mains adapted to deliver three-phase current, a number of 130

pairs of "Scott-connected" transformers having permanent primary connections with said mains, and an additional pair of similar transformers intended to have its feeding connections altered; in combination with two three-part multiple switches for changing the connections between said means and

the various coils of said additional transformer so as to alter the current phases in some of the coils thereof. 10

In testimony whereof, I have affixed my signature.

JOSEPH LAWTON DIXON.
